REVOLVING BIN

Filed Oct. 13, 1942

UNITED STATES PATENT OFFICE

2,311,130

REVOLVING BIN

Philip Rosenberg, New York, N. Y.

Application October 13, 1942, Serial No. 461,848

4 Claims. (Cl. 211—131)

This invention relates to revolving bins of the kind in which bin units are mounted one above another upon a common supporting shaft with capacity for rotation relative to the shaft and to one another.

Bins of this character have commonly been made in the past exclusively of metal. It has recently become desirable because of war conditions to find substitutes for metal, and to devise new structures employing non-metallic materials wherever possible as substitutes for old structures in which metals were freely used.

In my pending application Serial No. 461,847 for Revolving bins, filed concurrently herewith, I have disclosed and claimed a revolving bin structure in which the principal parts of the bin sections may all be made of non-metallic materials and united to form a sturdy unit through the very sparing use of metals in joining hardware.

The present invention has to do with a revolving bin of the type disclosed in my pending application, and more particularly with means for providing non-metallic outer wall members for the bin compartments and for securing such outer wall in place.

While the primary purpose of the present invention is to enable substitute materials to be employed for metals, it is to be understood that the invention is not limited to such use, but that it may be used to advantage in all metallic structures.

In my pending application Serial No. 426,403 filed January 12, 1942, for Bins, sector-like outer walls for revolving bins are disclosed, each wall being adapted to be thrust downward and fitted upon an upturned flange of the metallic floor member of the bin unit, together with latching means carried by the wall member and adapted to cooperate with the permanent dividers for holding the outer wall member fixedly but removably in place. Since the outer wall member of my prior application was snugly interlocked by a downward thrust with an upturned arcuate flange of the floor member, there was no freedom for the wall member to rock and no freedom for it to move bodily save in an upward direction, and the function of the latching means there employed was primarily to prevent lifting of the wall member vertically.

When the floor member is of non-metallic material and the outer wall member is of non-metallic material as in the present instance, the device of interfitting the wall member with an upturned flange of the floor member by a sim-

ple downward thrust is not available. The wall member cannot be interfitted with the floor member in a manner to securely preclude rocking movement, nor to preclude outward sliding movement. The attaching and latching means of my prior application Serial No. 426,403 is not, therefore, practically available to the same extent for use in a structure employing a non-metallic floor and outer wall members as in a structure employing metallic floor and outer wall members.

The primary object of the present invention is to provide, in combination with non-metallic floor, outer wall, and divider members, a novel means for attaching and latching the outer wall member to a permanent divider in such manner that rocking movement and outward sliding movement are prevented by the attaching and latching means themselves.

Other objects and advantages will hereinafter appear.

In the drawing forming part of this specification,

Fig. 1 is a view in elevation, broken away intermediate its ends for compactness of illustration, of a revolving bin embodying features of the present invention;

Fig. 2 is a fragmentary sectional view of the upper bin unit of Fig. 1, taken on the section line 2—2 looking in the direction of the arrows;

Fig. 3 is a fragmentary detail plan view on a larger scale than Figs. 1 and 2;

Fig. 4 is a fragmentary vertical sectional view taken upon the line 4—4 of Fig. 3, looking in the direction of the arrows;

Fig. 5 is a fragmentary vertical sectional view taken upon the line 5—5 of Fig. 4 looking in the direction of the arrows;

Fig. 6 is a view similar to Fig. 3, showing one of the outer wall sectors in the course of being attached to the bin unit; and

Fig. 7 is a detail sectional view taken upon the line 7—7 of Fig. 6, looking in the direction of the arrows.

The revolving bin comprises a base member 1 which carries a vertical central shaft 2 upon which the several bin sections 3, 3, are mounted with capacity for rotation relative to the shaft and relative to one another. Each bin section 3 comprises a central supporting sleeve 4. A floor member 5 of any suitable non-metallic material such as wood, Masonite, etc., is attached directly to the central sleeve as disclosed in my pending application Serial No. 461,847 and is further connected to and supported from the

central sleeve 4 through non-metallic permanent dividers 6, the dividers 6 being connected to the sleeve through brackets 7 and to the outer margins of the floor member through brackets 8. Each bracket 8 is provided at the outer lower corner of the permanent divider 6, to which it is attached. A rivet 9 passed through the bracket 8 and the divider 6 has impaled upon it a washer 10 and a spacer sleeve 11 at one side of the divider 6, and a washer 12 and a spacer sleeve 13 at the other side of the divider 6. The spacer sleeves 11 and 13 bear against the bracket 8 and against the associated washers, and the rivet 9 holds the assembly firmly and immovably clamped together.

As illustrated, five permanent dividers 6 are provided, and an outer wall sector 14 of non-metallic material is provided, of proper length to extend from one permanent divider to another.

The wall sector 14 is curved to conform substantially to the periphery of the floor member 5, and is formed with a groove 15 which receives the outer margin of the floor member 5, fits it snugly, and supports it. The wall member 14 is not ordinarily permanently secured in place, but is intended to be removable at the will of the user, so that the bin section can be adapted for various uses. The wall member 14, for example, will not be wanted when a sector of the bin is to be used as an open tray, or as a means for holding a cabinet section. It is evident, of course, that the joint formed between the floor member 5 and the channel of wall member 14 is not effective for securely holding the wall member 14 against outward movement, nor for preventing rocking movement of the member 14 out of engagement with the floor member 5.

For the purpose of preventing outward and rocking movement of the wall member 14, an angle bracket 16 is secured on the wall member 14 at either end thereof by rivets 17. The bracket 16 includes an inturned web 18 having an inwardly facing horizontal slot 19 formed in it. The bracket 16 is formed with bosses 20 at opposite sides of the permanent divider 6 and below the rivet 9. The web 18 is resilient enough so that it may be cammed and deflected away from the divider 6 as the wall member 14 is fitted into place. The web 18, however, is formed with an opening 21 adapted to receive the boss 20 and to fit around the boss when the wall member 14 and the web 18 attached thereto have been moved into finally assembled position as best illustrated in Fig. 4. In order to positively prevent disengagement of the boss 20 from the opening 21, a latch member 22 is provided on the web 18, being pivotally mounted on the web by a rivet 23. The latch member 22 is adapted to be swung downward as illustrated in Fig. 4 to a position in which it extends part way around the sleeve 11, and lies between the washer 10 and the web 18. The latch 22, together with the web 18, makes up a sufficient thickness completely to fill the space between the washer 10 and the bracket 8, so that the web 18 is permitted no play axially of the rivet 9, and is held firmly against the bracket 8 and in interfitting relation with the boss 20.

It will be seen that the boss 20 in conjunction with the sleeve 13 precludes rocking of the wall member 14, and that the boss 20 precludes outward bodily movement of the wall member 14, so that the wall member 14 is held firmly and securely against movement relative to the floor member 5 and the permanent divider 6.

When it is desired to remove the wall member 14, the latches 22 at opposite ends of the wall member are simply swung upward to a position like that marked 22a in Fig. 4, whereupon the wall member 14 can be detached and withdrawn by a movement which is substantially the reverse of that by which it was put in place.

The outer wall member 14 is desirably formed with a card holding groove 24 in the outer face 10 thereof. The groove 24 is formed with overhanging marginal portions, being illustrated herein as a dovetail groove. The base of the groove is not flat, but is made convex, as shown at 25, for supporting an inserted card in a convex condition.

I have described what I believe to be the best embodiment of my invention. I do not wish, however, to be confined to the embodiment shown, but what I desire to cover by Letters Patent is set forth in the appended claims.

I claim:

1. In a revolving bin unit, the combination with a non-metallic floor member, a plurality of permanent dividers, and a non-metallic arcuate outer wall segment, of means for securing the wall segment rigidly but removably in place comprising angle brackets affixed to the opposite ends of the wall segment, each having an inturned resilient ear formed with an inwardly opening slot and with an opening spaced from the slot, a stud device on each divider projecting from a face of the divider in the outer lower corner portion thereof and including a relatively restricted shank member, and a relatively large head member spaced from the adjacent face of the divider, said device adapted to have its shank portion received within the slot of the bracket ear, a further projecting member on the divider adapted to seat in the opening of the bracket ear when the ear has been thrust into assembled position, and a latch pivotally mounted on the ear and operable into position between the ear and the head member of the stud device to prevent side play of the bracket ear, and thereby to prevent disengagement of said further projecting member from the opening in the bracket ear.

2. In a revolving bin unit, the combination with a non-metallic floor member, a plurality of permanent dividers and a non-metallic outer arcuate wall segment formed with a groove to embrace and fit an outer marginal portion of the wall member, of means for removably securing the wall segment rigidly but removably in place comprising brackets affixed to the opposite ends of the wall segment, each having an inturned resilient ear formed with an inwardly facing slot, a stud device on each divider projecting from a face of the divider in the outer lower corner portion thereof and including a relatively restricted shank member and a relatively large head member spaced from the adjacent face of the divider, said device adapted to have its shank portion received within the slot of the bracket ear when the ear has been thrust into assembled position, cooperative means on the divider and on the ear adapted to be snapped into interfitting relation through the resiliency of the ear as the ear reaches assembled position, and latch means operable into position between the ear and the head member of the stud device to prevent side play of the ear.

3. In a revolving bin unit, the combination with a flat floor member, a plurality of permanent dividers, and an outer arcuate wall segment

formed with an inwardly facing channel to receive and fit upon an outer marginal portion of the floor member, of means for securing the outer wall segment rigidly but removably in place, comprising angle brackets affixed to opposite ends of the wall segment, each having an inturned resilient ear, said ear and divider including cooperating means for guiding the ear into assembled relation with the divider, and said ear and divider further including interlocking formations adapted to be snapped into interlocked relation as the ear reaches assembled position for opposing disarrangement of the parts.

4. In a revolving bin unit, the combination with a permanent divider and an outer wall segment of means for attaching the wall segment

rigidly but removably to the divider, comprising an inwardly projecting ear on the wall segment having an inwardly opening slot formed in it, and an opening formed in it at a substantial distance from the slot, a stud device on the divider having a relatively large head member and a relatively restricted shank member, the latter adapted to be received in the ear slot, a boss on the divider adapted to seat in the opening of the ear when the ear is moved into assembled position, and a latch carried by the ear and operable into position between the ear and the head member of the stud device to prevent side play of the ear when the parts are in assembled relation.

PHILIP ROSENBERG.
